UNITED STATES PATENT OFFICE.

HERMAN P. OLcott, OF WALLINGFORD, CONNECTICUT.

GAME APPARATUS.

Application filed January 26, 1923. Serial No. 614,962.

To all whom it may concern:

Be it known that I, HERMAN P. OLcott, a citizen of the United States, and a resident of Wallingford, Connecticut, have invented 5 certain new and useful Improvements in Game Apparatus, of which the following is a specification.

This invention relates to game apparatus particularly adapted to be used in the playing 10 of a game which, while more or less fascinating in its nature, is intended primarily to stimulate the development of certain muscles by necessitating the function of such in the execution of the plays incident to the 15 game.

The game in which the device embodying my invention is adapted to be used may be participated in by any number of players and briefly stated consists in the tossing of 20 a ball from one player to the other by means of the device and in catching the ball by means of the device when so delivered, certain rules as to penalties, scoring, etc., being observed to lend interest, develop skill and 25 promote competition among the players.

An important object of the invention is to provide a device of the character mentioned which may be easily varied or changed to meet varying conditions as the player or 30 players become more skillful and as certain muscles which the game is intended to stimulate become more and more developed.

Other objects of the invention will become apparent from the following description, 35 when taken in connection with the accompanying drawings in which:

Figure 1 is a view partly in section and partly in elevation of the device embodying my invention.

40 Figure 2 is a central sectional view of an insert or filler adapted to be associated with the device shown in Figure 1.

Figure 3 is a central sectional view of an insert similar to that shown in Figure 2 but 45 of a slightly different contour.

Figure 4 is a view in elevation showing a particular form of clamping screw, adapted to be used in securing the inserts shown in Figures 2 and 3, in position when associated 50 with the device shown in Figure 1.

In the drawings, wherein for the purpose of illustration is shown what I at present consider the preferred form of my invention, the numeral 5 indicates a ball-receiving 55 and delivering device, which comprises a cup-shaped or ball-receiving portion 6, so

formed as to provide a relatively deep cavity 7, the cup-shaped portion 6 being integrally attached or otherwise secured to an elongated handle 8. The cup-shaped portion 6 is provided centrally with an opening 9, and is cut away adjacent the opening to provide a recess 10, the purpose of which will hereinafter become apparent.

The device so far described is intended to be used by a more or less unskilled player, primarily because of the relatively deep cavity 7, which enables one to readily catch and easily retain the ball. Furthermore the device as illustrated in Figure 1 is particularly 70 adapted for the beginner for the reason that the same is relatively light and may be easily manipulated by a player the muscles of whom are insufficiently developed as a beginner to permit the use of a heavier device.

As the player continues to participate in the game, he not only becomes more skillful but those of his muscles, which are brought into play, become stronger and more developed. It is therefore desirable to vary 80 not only the weight of the device shown in Figure 1, but also desirable to change the contour of the recess 7 so that the catching of the ball is rendered more difficult. These two changes are made possible by an insert 85 or filler, indicated as a whole by the numeral 11. The curvilinear face 12 of this filler is such as to snugly fit the contour of the recess 7, whereas its face 13 is so shaped that when the insert or filler is positioned within the cup-shaped portion 6 the cavity thereof is rendered more shallow. It will be appreciated, therefore, that by inserting the 90 filler 11 the weight of the device shown in Figure 1 is increased to meet the requirements incident to the development of one's muscles, and at the same time the ball-receiving element 6 is so altered as to render the device as a whole well adapted to the 95 more skillful player.

In order to retain the insert 11 properly positioned within the cup-shaped portion 6, a clamp screw of the type shown in Figure 4 may be employed. This clamp screw is passed through the opening 9 and is run 105 down into a screw-threaded opening 15 formed centrally in the insert 11, the head 16 of the screw being adapted to snugly fit within the recess 10 formed adjacent the opening 9.

As the player's skill and muscular strength further develops, it becomes neces-

sary to again alter the device shown in Figure 1 in so far as its weight and the contour of the cavity 7 are concerned, and to effect this further alteration I provide an insert or 5 filler 17, shown in Figure 3. This insert is also formed with a screw-threaded opening 18, adapted for the reception of the clamping screw 14 and is of such a shape as to snugly fit the cavity 7. It will be noted, 10 however, that the insert 17 is somewhat thicker than the insert 11 and as a result of this variation in thickness the cavity 7 is rendered more shallow when the insert 11 is removed and the insert 17 substituted there- 15 for. While I have shown only two inserts, namely those indicated by the numerals 11 and 17 respectively, it will be understood that as many of these inserts, varying in weight and shape, may be employed as are 20 deemed necessary to take care of the player's gradual development of skill and strength. It will be further understood that while I have not specified the particular material from which the device shown in Figure 1 25 and the inserts shown in Figures 2 and 3 are constructed, such materials as aluminum, wood, fiber or similar materials may be employed.

While I have shown and described what I 30 at present consider the preferred form of the device, it will be understood that various changes in the size and shape of parts embodied therein may be resorted to without departing from the spirit of the invention 35 or scope of the subjoined claims.

Having thus described my invention, I claim:

1. A game apparatus comprising a ball-receiving element, and an insert arranged within said element, said insert being of a given contour and adapted to be removed to vary the contour of the ball-receiving element. 40

2. A game apparatus comprising a ball-receiving element, an insert arranged within said element, said insert being of a given contour and adapted to be removed to vary the contour of the ball-receiving element, and means for locking said insert in position within said ball-receiving element. 45

3. In a game apparatus, the combination with a ball-receiving pocket having a given contour, of a plurality of inserts having different contours, said inserts being adapted to be positioned within and removed 50 from said ball-receiving element to vary the contour of said ball-receiving element.

4. In a game apparatus, the combination with a ball-receiving pocket having a given contour, of a plurality of inserts having different contours, said inserts being adapted to be positioned within and removed from 55 said ball-receiving element to vary the contour of said ball-receiving element, and means common to all of said inserts for retaining them properly positioned within said ball-receiving element. 60

In testimony whereof, I have affixed my signature to this specification.

HERMAN P. OLCOTT.
